A. SNOW, Jr.

ORNAMENTATION OF GLASSWARE.

No. 17,380.

Patented June 7, 1887.

UNITED STATES PATENT OFFICE.

ANDREW SNOW, JR., OF NEW BEDFORD, MASSACHUSETTS.

DESIGN FOR THE ORNAMENTATION OF GLASSWARE.

SPECIFICATION forming part of Design No. 17,380, dated June 7, 1887.

Application filed March 14, 1887. Serial No. 230,911. Term of patent 7 years.

To all whom it may concern:

Be it known that I, ANDREW SNOW, Jr., a citizen of the United States of America, residing at New Bedford, in the county of Bristol and State of Massachusetts, have invented certain new and useful Improvements in Designs for the Ornamentation of Glassware; and I do hereby declare the following to be a full, clear, and exact description of the invention, 10 such as will enable others skilled in the art to which it appertains to make and use the same, reference being had to the accompanying photograph, and to letters of reference marked thereon, which forms a part of this specification.

Reference being had to photograph showing my new design, the figure is a top view of a dish. D, being a star shaped figure forming a center around which is shown the ornamental 20 band composed of figures A, B, and C, is more fully described hereinafter.

My new design for the ornamentation of glassware consists of a circular band composed of an angulated ribbon, B, of pyramidal projections. Between the angles of said ribbon fan-like figures A, C are arranged, formed of corrugated or prismatic lines, the rays of fans C diverging from a common point, e, toward the center star, D, composed of a series of 30 prisms, f, intersecting each other, and forming the polygonal pyramid E and numerous facets at its center. The lines of fans C, radiating from the inner angles, fill in between the points of star D.

The essential features of my new design, and which impart novelty and artistic effect to it, are, first, the ornamental band composed of a series of angles filled in with pyramidal projections and corrugated or prismatic fan-like 40 figures between the angles; also, a star formed of crossing prisms with a polygonal pyramidal center and numerous facets at point of intersection.

Having described my design, I claim—

1. The design for the ornamentation of 45 glassware herein shown and described, the same consisting of a circular band composed, essentially, of an angulated ribbon, B, presenting parallel lines, the space between them being filled in with pyramidal projecting points. 50

2. The design for the ornamentation of glassware herein shown and described, the same consisting of a circular band composed, essentially, of an angulated ribbon, B, presenting parallel lines, the space between them being 55 filled in with pyramidal projections, the inner and outer angles formed by said ribbon being filled in with corrugated or prismatic fans A and C.

3. The design for the ornamentation of glassware herein shown and described, consisting of a center star, D, composed, essentially, of crossing prisms g, formed by parallel lines crossing each other at center, forming a polygonal pyramid, and having the ornaments 65 within the margin of the outer points constituting a circle, as shown.

4. The design for the ornamentation of glassware herein shown and described, the same consisting of a circular band composed, essentially, of an angulated ribbon, B, formed of 70 parallel lines filled in with pyramidal projections, the angles formed by ribbon being filled in with fan-like figures A and C, of corrugated or prismatic lines, and the star center D of 75 crossing prisms g, having a polygonal pyramid center, E, and numerous facets at point of intersection.

In testimony whereof I affix my signature in presence of two witnesses.

ANDREW SNOW, JR.
